UNITED STATES PATENT OFFICE.

JULIUS FREDERIK GEORG PØUL HARTMANN, OF COPENHAGEN, DENMARK.

ELECTRODE FOR JET-WAVE COMMUTATORS AND INTERRUPTERS.

Application filed May 19, 1925. Serial No. 31,350.

To all whom it may concern:

Be it known that I, JULIUS FREDERIK GEORG PØUL HARTMANN, a subject of the King of Denmark, residing at Copenhagen, Denmark, have invented new and useful Improvements in or Relating to Electrodes for Jet-Wave Commutators and Interrupters; and I do hereby declare the following to be a full, clear, and exact description of the same.

This invention relates to jet-wave commutators and interrupters, and particularly to electrodes or combinations or arrangements of electrodes to be used in such devices. Apparatus of this character are described for instance in my U. S. patent specifications Nos. 1,306,335 and 1,365,491, and include a wave-shaped conductive liquid jet or shortly a jet-wave, preferably of mercury, which moves on in the direction of the axis of the wave figure and strikes or comes into contact with one or more electrodes.

These electrodes have hitherto been made of solid metal, but in accordance with the present invention one or more of the electrodes with which the jet-wave comes into contact or parts of these electrodes is or are formed as one or more conductive liquid jets, preferably mercury jets, through which the jet-wave passes and through which current may be led into or out from the jet-wave. It has been found in practice that when the jet or jets of such a jet-electrode have properly chosen dimensions and velocity the jet-wave will pass the jet-electrode without being seriously damaged, and that certain advantages which will appear from the following may be obtained by using such jet-electrodes instead of solid electrodes.

The jet-electrode may be formed as a jet-comb, that is a series of jets emitted from holes in the side of a tube or box, through which the current may be led into the jets of the electrode, and these jets may strike a conducting bar or piece (a so-called counter-piece) through which current may be led into the jets and further into the jet-wave in order to wholly or partly throw off the load of current of said tube or box.

Other features of the invention and the advantages obtained thereby will appear from the following description of the embodiments shown on the accompanying drawings, in which—

Figure 1 is a diagrammatic view of the

essential parts of a jet-wave rectifier or commutator of known type which is provided with solid electrodes, this view being shown for the purpose of comparison only in order to make the invention more easily understood;

Figures 2 and 3 are a front view and a plan view respectively of a jet-comb-electrode constituting an embodiment of the invention;

Figure 4 is a plan view of a jet-comb-electrode provided with a counter-piece;

Figures 5-7 are diagrammatic views of jet-wave commutators provided with jet-comb-electrodes;

Figure 8 is a plan view of a double jet-comb-electrode provided with counter-pieces;

Figure 9 is a diagrammatic view of a jet-wave commutator, in which a double main-electrode consisting of jet-combs is arranged above an auxiliary electrode, and

Figures 10 and 11 are a plan view and a front view respectively of a double electrode comprising both liquid jets and solid electrode elements.

Referring now to Figure 1 the jet-wave commutator shown therein includes a jet-wave J which issues from a nozzle N and moves on in the direction of the axis of the wave figure and strikes a two-part electrode E₁, E₂, the component parts E₁ and E₂ of which ordinarily are separated by an insulating wall P with a sharpened edge which cuts the bends of the jet-wave. The latter being during its movements towards the electrode E₁, E₂ in constant touch with an auxiliary electrode E', will alternately connect this latter electrode with the electrode parts E₁ and E₂. The jet-wave together with the double-electrodes E₁, E₂, and the auxiliary electrode E' thus forms a commutator which may be used for the rectification of an alternating voltage. For this purpose the waves are generally produced by the co-action between a constant magnetic field F and an auxiliary alternating current, which is synchronous with the voltage to be rectified. The current may be delivered from the secondary T of a transformer and sent into and out from the jet through the nozzle N and an auxiliary electrode E. Furthermore in order to make the commutator serviceable for the rectification of the said alternating voltage the double-electrode is, and

must be, adjusted at such a distance from the

field, that the jet-bend is cut nearly at the moment in which the alternating voltage alters its sign.

It has been found that one or more of the solid electrodes of such a jet-wave commutator may advantageously be substituted by jet-electrodes and preferably jet-comb electrodes, but such electrodes may also be used in any other type of jet-wave commutators as well as in jet-wave interrupters and broadly speaking in any apparatus having a conductive liquid jet for the closing or interruption of an electric circuit.

The jet-comb may be produced by means of a pipe R, Figures 2 and 3, in the side wall of which the holes for the jets j, j', j'' are bored. The waves of a jet-wave commutator will with properly chosen dimensions and velocity of the comb-jets pass the jet-comb without being seriously damaged as above indicated. The current is led into the jet-wave through those comb-jets which at any moment are in contact with the jet-wave.

In order to partly or completely exempt the pipe R from carrying current the jet-comb-electrode may be furnished with a solid bar or piece B, Figure 4 (the counter-piece) against which the jets of the comb are directed, and through which the current may be led into the comb-jets and therefrom into the jet-wave.

Some applications of the jet-comb-electrode will now be described by way of example. First it may be used as an auxiliary electrode in a jet-wave commutator. In the commutator shown in Figure 5 it is used for the introduction of the main current, that is to say the rectified current, into the jet-wave J of the commutator. The quality of the jet-comb-electrode of not damaging the jet-wave is here of main importance. The jet-comb-electrode E' can be placed just above the double-electrode E_1, E_2 , thus reducing the length of the bend of the jet J extending between the electrodes E' and E_1, E_2 , and thereby the resistance which the main current must overcome. In this way it has proved possible to highly reduce the ohmic loss of the jet-wave commutator. It should in this connection be mentioned that the jet-comb-electrode also may be used instead of the solid electrode E in Figures 1 and 5 and thus for introducing the auxiliary current into the jet J.

The jet-comb when used as an auxiliary electrode need not be placed cross-wise to the axis of the jet-wave J. It may be arranged along said axis as shown by E' in Figure 6. The only condition which in this case must be fulfilled is that the jet-comb covers half a wave-length of the jet J.

In the next application to be considered the jet-comb-electrode is used for the component parts E_1 and E_2 of the main elec-

trode as shown in Figure 7. This application is of high importance in that it makes it possible to dispense with the insulating wall P shown in Figure 1. If this wall is made of a proper material, say fused quartz, the wear due to the commutator spark can be reduced to a tolerable amount, but if jet-combs are used the double electrode is in a way subjected to no wear at all and will last practically forever. The two combs E_1 and E_2 are to be placed symmetrically in such positions that the commutation-sparks are formed between the innermost jet in each comb and the jet-wave, and the combs must be positioned at such a distance from each other, that the bend of the jet J comes into contact with the first jet j_2 of the comb E_2 before losing contact with the last jet j_1 of the comb E_1 or vice-versa. The distance will be somewhat larger than is to be expected from a geometrical consideration as the jet bend in leaving a jet of the comb draws a string from the latter, which string only bursts after having reached a certain length. It has been found that the certainty with which the commutation takes place is a comparatively very high one. In Figure 7 the electrode E' also includes a series of conductive jets j . Figure 8 shows how the double electrode may be provided with bars B_1 and B_2 to reduce the current load of the pipes R_1 and R_2 as well as the current load of the electrode-jets. Figure 8 may be considered as a top view of both of the double-electrodes shown in Figures 7 and 9.

The jet-comb double electrode makes it possible to construct a commutator with an auxiliary electrode placed beneath the main electrode in the manner indicated in Figure 9. To avoid spraying of the mercury the auxiliary electrode E' is here composed of knives or wedges, but generally a jet-comb double electrode may be arranged above a single electrode of any description.

It is now obvious that, unless the jet-comb double electrode is to be used in connection with an auxiliary electrode E' arranged below the main electrode as in Figure 9, it is not at all necessary that the whole of the two sides E_1 and E_2 consists of jets. Some of the jets or all except the innermost jets j_1 and j_2 , Figure 7, may be replaced by solid material for instance by steel wedges. The electrode then takes the form shown in Figures 10 and 11. Here too, the interruption takes place between two jets, namely, the main jet J and the jet j_1 or j_2 , and thus the electrode is subjected to no wear as the commutation-spark does not attack the wedges. The jet-pipes R_1 and R_2 may be connected directly with the electrode parts E_1 and E_2 respectively or they may also be insulated and connected with the parts E_1 and E_2 through resistances. The jets j_1 and j_2 may

be directed against counter-pieces connected directly with the parts E_1 and E_2 respectively, or between the counterpieces and the parts E_1 and E_2 , there may be inserted resistances 5 for the diminishing of the short-circuiting current arising during the commutation.

Furthermore in a complete jet-comb one or more jets may be insulated from the remainder for the purpose of introducing resistances or other devices between the separate jets or between the jets and the remainder of the electrode.

Having thus fully described my invention I claim as new and desire to secure by Letters Patent:

1. In an electric jet-wave apparatus, the combination of a conductive jet-wave and an electrode including a conductive liquid jet through which the said jet-wave passes and 20 through which current may be led into or out from the jet-wave.

2. In an electric jet-wave apparatus, an electrode consisting of a hollow member having in its side a series of holes through 25 which conductive liquid jets issue, and a conductive jet-wave adapted to pass through said jets to establish or break electric contact between said jet-wave and jets.

3. In an electric jet-wave apparatus, an 30 electrode consisting of a hollow member having in its side a series of holes through which conductive liquid jets are emitted, and a conductive counter-piece struck by said jets, through which counter-piece current may be led into these jets.

4. An electric jet-wave commutator, comprising means for producing a conductive

jet-wave, an electrode adapted to be in constant touch with the said jet-wave during its motions, and a double-electrode, the two 40 sides of which are adapted to be alternately connected with the first named electrode through said jet-wave, the innermost part of each side of said double-electrode consisting of at least one conductive liquid jet, the 45 said double-electrode being so arranged that the interruption between the jet-wave and each side of the said double-electrode takes place at said liquid jet.

5. An electric jet-wave commutator, comprising means for producing a conductive jet-wave, an electrode adapted to be in constant touch with the said jet-wave during its motions, and a double-electrode the two 55 sides of which are adapted to be alternately connected with the first-named electrode through said jet-wave, each side of said double-electrode consisting of a hollow member having in its side a series of holes through which conductive liquid jets are 60 emitted, and the two sides of the double-electrode being arranged symmetrically with relation to the axis of the said jet-wave in such positions that the commutation sparks are formed between the innermost jet of 65 each electrode-side and the said jet-wave.

6. In an electric jet-wave-apparatus, an electrode adapted to be in constant touch with the jet-wave, said electrode including a series of conductive liquid jets through 70 which the jet-wave passes.

In testimony whereof I have affixed my signature in presence of two witnesses.

JULIUS FREDERIK GEORG POUL HARTMANN.
